VEHICLE DESTINATION SIGN MECHANISM

Harry Yale Mageoch, Havertown, Pa., assignor, by mesne assignments, to H. K. Porter Company, Inc. of Pittsburgh, a corporation of Pennsylvania

Application October 11, 1954, Serial No. 461,365

8 Claims. (Cl. 40—95)

The present invention relates generally to vehicle station designation sign mechanisms wherein the sign curtain is relatively long and narrow and is more particularly concerned with an improved construction thereof affording certain functional advantages.

It is an object of the invention to provide a vehicle designation sign having a relatively long and narrow sign curtain wherein the latter is adapted to travel over and be positioned upon a transversely curved or bowed support of light transmitting material whereby the range of sign visibility is increased.

It is another object of the invention to provide a vehicle designation sign having a relatively long and narrow sign curtain adapted to be wound upon a spaced pair of relatively short rollers wherein the curtain is constantly under lengthwise tension and wherein the rollers may have their relative speeds automatically varied as required to compensate for their changing curtain roll diameters as the curtain is transferred from one roller to the other when the sign is operated to change its station designation.

It is a further object of the invention to provide a vehicle designation sign of the class referred to wherein the means to tension the curtain and to vary the roller speeds is disposed externally of the rollers thereby facilitating the employment of relatively short rollers upon each of which is adapted to be wound a relatively long length of curtain material.

It is a still further object of the invention to provide a vehicle designation sign of the class referred to wherein a drive is arranged to commonly actuate said rollers and wherein the means to tension the curtain and to vary the roller speeds forms a part of the driving arrangement.

It is another object of the invention to provide a vehicle designation sign of the class referred to wherein a relatively long drive shaft, directly connected to one roller, is connected through a shaft-aligned spring-loaded barrel to the other roller, whereby the one roller is adapted to be positively actuated while the other roller is adapted to be yieldingly actuated when the drive shaft is turned, to the end that the curtain may constantly be under tension and the rollers may have their relative speeds automatically varied when the sign is operated to change its sign designations.

Other objects and advantages of the invention will be apparent hereinafter, it being understood that the present invention consists substantially in the combination, construction, location and relative arrangement of parts, all as described in detail in the following specification, as shown in the accompanying drawings and as finally pointed out in the appended claims.

In the accompanying drawings:

Figure 1 is a plan view of the vehicle station designation sign of the present invention, showing in particular the elongated, transversely curved path of traverse of the curtain between the opposite end rollers of the sign;

Figure 2 is a rear elevational view of the sign with

2

portions of the frame broken away to show certain operating details;

Figure 3 is a vertical cross-sectional view showing the relative disposition of parts of the sign and particularly 5 showing the hand operated driving arrangement for the roller actuating drive shaft as taken along the line 3—3 of Figure 1;

Figure 4 is a cross-sectional view generally similar to Figure 3 as taken along the line 4—4 of Figure 1;

10 Figure 5 is a horizontal cross-sectional view through the sign showing the relative disposition of its component parts in plan as taken along the line 5—5 of Figure 2 with portions of the curtain frame broken away to show the transversely curved support or backing for the curtain;

15 Figure 6 is a vertical cross-sectional view through the sign showing the constructional details of the arrangement for yieldingly driving one of the curtain rollers through the spring-loaded barrel and associated parts as taken along the line 6—6 of Figure 5;

20 Figure 7 is a vertical cross-sectional view through the spring-loaded barrel showing an anchor for one end of the spring, as taken along the line 7—7 of Figure 6;

25 Figure 8 is another vertical cross-sectional view through the spring-loaded barrel showing an anchor for the opposite end of the spring as taken along the line 8—8 of Figure 6;

30 Figure 9 is still another vertical cross-sectional view through the spring-loaded barrel showing the arrangement whereby the barrel tube may rotate relative to the spring-biased shaft as taken along the line 9—9 of Figure 6;

35 Figure 10 is a horizontal cross-sectional view through the upper end of a curtain roller showing the curtain anchoring arrangement as taken along the line 10—10 of Figure 6; and

40 Figure 11 is a vertical cross-sectional view through one of a pair of spaced curtain idler rollers disposed at opposite ends of the transversely curved curtain support, as taken along the line 11—11 of Figure 5.

Referring now to the drawings and more particularly 45 to Figures 1 to 5 thereof, it will be observed that the station designation sign unit of the present invention includes a box-like frame or support for an illuminated station-designating curtain 10, which is relatively narrow in width and may be of any desired length sufficient to have printed thereon in longitudinally spaced relation the names of a number of different stations along the route of travel of the vehicle equipped with the sign. The housing for this curtain includes a pair of horizontally disposed, parallel top and bottom plates 11 and 12 which are suitably secured together in vertically spaced relation, as shown, to support therebetween a vertically disposed, elongated member 13 formed of any suitable light-transmitting material, such as, transparent or translucent glass or plastic sheet material, e. g., "Plexiglas,"

55 or even sheet metal suitably apertured for the transmission of light therethrough. This light-transmitting member 13, which is vertically disposed between corresponding outer edges of the top and bottom plates 11 and 12, is transversely curved lengthwise of its support so as to provide an outwardly bowed flat surface over which the curtain 10 may pass as it is shifted lengthwise of its support 13 in either direction to display the name of any one of the stations printed on the curtain. Se- 60 cured at each opposite end of the curtain support is an

65 idler roller 14, which idler rollers are so vertically disposed as to permit the curtain 10 to pass tangentially over the rollers and on to the transversely curved outer surface of its light-transmitting backing or support 13 extending lengthwise between the idler rollers.

70 The curtain housing formed of the top and bottom plates 11 and 12 and the curtain support 13, as above described, is suitably secured in front of a supporting

structure, designated generally by the reference numeral 15, for a pair of curtain rollers 16 and 17. This supporting structure for the curtain rollers 16 and 17 includes a pair of vertically spaced top and bottom plates 18 and 19, the top plate being in the form of a downwardly presenting channel having a frontal wall 20 which is secured to the top plate of the front curtain housing by a plurality of longitudinally spaced angled clip members 21, while the bottom plate 19, of Z-shaped cross-section, is provided with an upstanding flange 22 which is secured to the bottom plate 12 of the curtain housing by a plurality of longitudinally spaced angled clip members 23.

Suitably supported between the top and bottom plates 18 and 19 of the roller-supporting structure is a horizontally extending lamp-socket supporting rail 24, this latter rail being preferably secured rigidly in position by a plurality of angled clip members 25 suitably secured to the top plate 11 of the front curtain support. The rail 24 suitably mounts a plurality of lamp sockets 26, each of which is adapted to receive a lamp bulb 26^a for illuminating the station-designating curtain 10 by light transmitted from the lamps to and through the transversely curved support or backing 13 for the curtain.

As most clearly appears in Figures 1 and 2, the curtain rollers 16 and 17 are respectively disposed in vertically extending relation at opposite ends of the vertically spaced plates 18 and 19 of the supporting structure 15. These rollers 16 and 17 are generally alike in that each includes, as best shown in Figure 6, a curtain-receiving tube 27 into the opposite ends of which are press-fitted or otherwise nonrotatably secured the central hub 28 of an annular flange 29, the hub of which flange is centrally fitted with a roller-supporting shaft. Thus, each of the rollers 16 and 17 is provided at its lower end with a downwardly presenting shaft 30 and at its upper end with a coaxial upwardly presenting shaft 31.

As appears most clearly in Figures 2 and 6, the lowermost shafts 30—30 of the vertically disposed curtain rollers 16 and 17 are respectively journaled in bearing members 32—32 of such design and construction as to facilitate lateral displacement of the shafts 30—30 from their bearings for bodily removal of the rollers when and as desired. These bearings 32—32 for the bottom end shafts 30—30 of the curtain rollers may be of any conventional form, and form no part of the present invention. The top end shafts 31—31 of the curtain rollers 16 and 17 are respectively journaled in suitable bearing members 33—33 fixed to and carried by the top plate 18 of a curtain roller-supporting structure 15, these bearing members 33—33 being each preferably in the form of an elongated block of square or rectangular section having its upper end secured rigidly to the plate 18, as by a screw 34, and having its lower end socketed, as at 35, for rotatably receiving the upper extremity of the shaft 31 at the top end of each curtain roller. As also appears most clearly in Figures 2 and 6, the top end shafts 31—31 of the curtain rollers each have keyed thereto a bevel gear 36, rotation of which in either direction effects corresponding rotation of the curtain roller immediately associated therewith.

Suitably journaled within the curtain roller-supporting structure 15 immediately beneath the top plate 18 thereof is a longitudinally extending drive shaft 37. This drive shaft 37 extends generally from above the curtain roller 16 to a point approximately midway of the roller-supporting structure 15, its left hand end, as viewed in Figure 2, being projected through the bearing block 33 for rotatable support thereby, while its right hand end, as best shown in Figure 6, is rotatably journaled in a bearing member 38 which forms part of the curtain sign operating mechanism which will be described in further detail hereinafter and which is suitably supported by the top plate 18 of the curtain roller-supporting structure 15. The freely projecting left hand extremity of the shaft 75

37 is nonrotatably fitted with a bevel gear 39 which is in meshed engagement with the bevel gear 36 of the curtain roller 16, while keyed to the right hand end of the shaft 37 is a bevel gear 40.

Referring now more particularly to Figures 6 to 9, inclusive, it will be observed that the free extremity of the longitudinally extending shaft 37 is splined, as at 41, to the end hub 42 of a coaxially extending roller tube 43 which is revolvable with the shaft 37 about the longitudinal axis thereof. The opposite, i. e.—right hand, end of this roller tube 43 is fitted with a centrally apertured hub member 44. Also, it will be noted that the roller tube 43 is indented, as at 45, adjacent its left hand end to provide an internal rib 46 extending partially about the circumference of the roller tube, which latter tube is further provided along its full length with a longitudinally extending indentation 47 to provide an internal rib 48 disposed substantially midway between the opposite ends of the circumferentially extending internal rib 46.

Fitted within the roller tube 43 is a spring retainer disc 49, the circumferential edge of which is notched, as at 50, to receive therein the longitudinally extending internal rib 48 of the roller tube 43, the disc 49 being thus retained within the roller tube against rotation relatively thereof while being movable axially thereof. The disc 49 is restrained against axial movement toward the left hand end of the roller tube by the circumferentially extending internal rib 46 against which it normally abuts.

The disc 49 is centrally recessed, as at 51, to receive therein one end of a spring-supporting tube 52, the opposite or right hand end of this tube 52 terminating just short of and being in axial alignment with the central aperture of the end hub 44 of the external roller tube 43. It will be noted that the tube 52, which is of substantially smaller diameter than the tube 43, is disposed concentrically within the latter tube.

Extending axially of the spring-supporting tube 52 toward the right hand curtain roller 17 is a shaft 53, the freely projecting end of which is rotatably journaled in a socket 54 suitably provided therefor in the right hand bearing block 33. Keyed to this shaft 53 is a bevel gear 55 disposed for constant mesh engagement with the bevel gear 36, which is fixedly associated with the curtain roller 17. The portion of the shaft 53 immediately to the left of its bevel gear 55 is rotatably journaled within the hub 44 of the external roller tube 43, while the freely projecting left hand end portion of this shaft 53 projects into and serves as a support for the internal spring-supporting tube 52.

Embracing the internal spring-supporting tube 52 is a coiled spring 56, the right hand terminal end 57 of which is extended diametrically through the tube 52 and that portion of the shaft 53 which projects into said tube, 55 while the left hand extremity of the coiled spring 56 is provided with a terminal extremity 58 which projects through and thus is secured to the disc 49. The shaft 53 constitutes in effect an axial extension of the tube 52, which shaft tube assembly is supported for rotation within three axially spaced bearings respectively provided by the disc 49, the hub 44 and the end bearing block 33.

It will be observed from the foregoing that upon rotation of the shaft 38 in either direction the roller tube 17 will be correspondingly rotated through the intervention of the spring-connected concentric tubes 43 and 52 and the meshed bevel gears 55 and 36, the gear 55 being driven by the shaft 53 and in turn driving the gear 36 fixed to the shaft 31 of the curtain roller 17.

For operating the sign mechanism of the present invention, that is, for effecting rotation of the main drive shaft 37 in one direction or the other in order to wind the curtain 10 upon one of the curtain rollers as it is unwound from the other and vice versa, the unit includes an operating assembly, designated generally by the reference numeral 59, preferably disposed centrally of the

unit for top-side operation thereof. As appears most clearly in Figures 3 and 6, this operating mechanism 59 includes a centrally apertured plate 60 which is secured, as at 61, in laterally offset relation to the top member 18 of the curtain roller-supporting structure, this plate 60 being of inverted cup-shaped form and having a bottom closure plate 62 which is suitably secured to the depending flange 20 of the member 18 by an angle bracket 63. Preferably, the outer overlapping edges of the cup-shaped plate 60 and its bottom closure plate 62 are secured together as by bolts 64. Disposed within the hollow casing formed by the plate members 60 and 62 is a drive clutch assembly 66 having a drive shaft 67 projecting upwardly through the apertured plate 60, the projecting end of this drive shaft 67 being fitted with a hand operated crank member 68. The drive end of the clutch assembly 66 is provided with a revoluble spur gear 69, the teeth of which are in mesh engagement with those of a driven spur gear 70 suitably journaled for rotation about a vertically disposed shaft 71 fixed, as at 72, to the top member 18 of the curtain roller-supporting structure.

Suitably fixed to and revoluble with the spur gear 70 is a bevel gear 73, which latter gear is in mesh with the bevel gear 40 fixed to the main operating shaft 37. It will be noted that the lower end of the supporting shaft 71 about which the spur gear 70 and the bevel gear 73 are revoluble as a unit projects into and supports member 38 which serves as a bearing for the shaft 37.

While any suitable clutch assembly, such as that designated 66, may be employed for driving the shaft 37 in either direction upon corresponding rotation of the crank 68, it is preferred to employ for this purpose a clutch assembly of the construction shown and described in my copending application, Serial No. 273,391, filed February 26, 1952, which clutch assembly is operative to permit free turning of the crank 68 in either direction when the crank handle is operated to rotate gear 69 in either direction but which resists turning of said gear 69 when rotative effort is applied thereto by the crank handle at the outer surface of the gear. Thus, when the crank is rotated to present in viewing position a preselected portion of the sign curtain 10, the latter is held secure against creeping in either direction. Inasmuch as the nonreversing clutch mechanism 66 may be of any desired construction and thus does not constitute an indispensable part of the present invention, the description of such a clutch mechanism as it appears in the aforesaid pending application is included herein and made a part hereof by reference only.

As has been previously indicated, the printed curtain 10 is adapted to closely overlie the transversely curved light transmitting support or backing 13 during its traverse from one curtain roller to the other, it being apparent, of course, that opposite end portions of the curtain are respectively wound about the rollers 16 and 17, the general arrangement being such that as the curtain is wound upon one of these rollers it is unwound from the other. The idler rollers 14-14 are each freely rotatable about fixed shafts 74 suitably secured in vertically disposed position between the top and bottom plates 11 and 12 of the front curtain support. As shown in Figure 11, these idler rollers 14-14 each includes a tube 75 internally fitted at its opposite ends with hubs 76 which are revolvably journaled on the fixed shaft 74. Preferably, the opposite ends of the curtain 10 are respectively secured to the rollers 16 and 17 by means of retainer pins which press and retain the ends of the curtains in longitudinally extending indented seats 78 suitably formed in the peripheral surfaces of the rollers.

In the operation of the curtain sign mechanism of the present invention, the curtain rollers 16 and 17 are initially removed from their respective supports so as to permit each opposite end portion of the curtain to be wrapped several turns about each of the rollers, follow-

ing which all of the slack portion of the curtain is wrapped about the right hand roller 17, leaving extended between the rollers only such length of the curtain as is necessary to more or less snugly overlie the transversely curved support 13 therefor upon replacement of the rollers into their operative position. However, before replacing the roller 17 in its operative position, that is, with its bevel gear 36 in mesh with the bevel gear 55, the latter gear is turned by hand an amount sufficient to impart to the coiled spring 56 a predetermined tension, which tension may vary, depending upon the length of the curtain, its weight and other factors, such as, the amount of friction existing between the curtain and its transversely curved backing or support 13. Thereupon, without releasing the tension imposed upon the coiled spring 56, the roller 17 is replaced in operative position, it being apparent that upon meshing of the bevel gears 36 and 55 the established tension of the coil spring 56 will be retained by the tube 43, which will then be held stationary by reason of its nonrotatable securement to the main shaft 37, which latter, of course, remains stationary so long as the crank 68 of the operating mechanism 59 is not moved.

With the curtain 10 thus disposed in position over its support 13 and the mechanism preliminarily spring-loaded as just described, the mechanism is ready for operation to shift the curtain wound upon the roller 17 lengthwise across the support 13 for winding about the roller 16, a sufficient length of the curtain being taken off of the roller 17 to present to view the name of any one of the stations printed on the curtain.

At this point, it should be noted that as the curtain is withdrawn from one roller and wound upon the other, the overall diameters of the rolls of the curtain on the rollers 16 and 17 will vary, in consequence of which the linear speed of travel of the curtain about the rollers 16 and 17 will vary in accordance with the diameters of the curtain rolls on the rollers. Thus, assuming that the major length of the curtain is wrapped about the roller 17, it will be apparent that for each succeeding revolution of this roller 17 in curtain winding direction there will be a tendency to increase the rotative speed of the roller 16. Exactly the same condition would prevail should more of the curtain be wound about the roller 16 than about the roller 17, in which case continued rotation of the roller 16 in curtain winding direction would tend to cause an increased speed of rotation of the curtain roller 17.

Conversely, when either roller contains a minor portion of the curtain, the continued rotation of said roller in curtain winding direction would result in reduced speed of rotation of the roller containing the larger amount of curtain. Obviously, were the rollers connected together by a rigid interconnecting shaft, any such variation in relative rotative speeds of the two rollers would render impossible their conjoint operation, as is necessary in the case of a sign mechanism in which a length of curtain is wound upon one roller simultaneously as it is unwound from another.

The mechanism of the present invention, including particularly the spring-interconnected tubes 43 and 52 disposed in intervening relation with respect to the shafts 37 and 53 respectively geared to the rollers 16 and 17, compensates for any differential in the rotative speeds of the rollers 16 and 17 and at the same time maintains a constant tension on the curtain 10 as it is rolled up from a small diameter roll on one roller to a larger diameter roll on the other roller, as well as when it is rolled up from a large diameter roll on one roller to a smaller diameter roll on the other roller.

In the mechanism of the present invention, as the curtain 10 is caused to traverse its light-transmitting support or backing 13 so that it is wound up on one roller simultaneously as it is unwound from the other, which traverse is, of course, effected by operation of the crank 68 and

its associated parts, the coil spring 56 will gradually wind or unwind, depending upon the direction of rotation of the crank 68, to permit increased or decreased speed of rotation of one roller relatively to the other. The coil spring 56, being under constant tension, tends constantly to maintain the curtain 10 wound upon the curtain roller 17 and thus the portion of the curtain which extends freely between the two rollers is held constantly taut. It will be apparent that the extent of winding and unwinding of the coil spring 57 as the curtain is wound upon one roller and simultaneously unwound from the other will depend upon the length of curtain which is withdrawn from one roller for winding about the other, and that upon each revolution of either roller in curtain winding direction the coil spring 56 will be wound or unwound a relatively slight extent.

An important feature of the present invention is the utilization of a relatively narrow strip of curtain material drawn over a curved surface of substantial length extending between a pair of spaced curtain rollers, all as herein shown and described. By employing such a curtain, the station names may be printed successively along the length of the curtain each within a space providing for wide angle view thereof when presented in station indicating position. Because the station names are printed lengthwise of the curtain, an ample supply of curtain is required, it being apparent that in the sign mechanism of the present invention each of the spaced rollers is designed and operative to receive as many turns of the curtain as may be required and that either one of the rollers may be curtain-wrapped to a much greater diameter than the other without disturbing in any way proper operation of both rollers when the curtain is shifted from one to the other.

It is important to note also that the coil spring 56 is disposed externally of the rollers and in consequence may be and preferably is of a length considerably greater than that of the roller with which it is immediately associated so that said roller may be sufficiently spring-loaded to maintain the curtain taut during all conditions of operation and for adjusted positions thereof.

It will be understood, of course, that the present invention is susceptible of various changes and modifications which may be made from time to time without departing from the general principles or real spirit thereof as hereinbefore described, and it will be understood accordingly that it is the intention to claim the same broadly, as well as specifically, as indicated by the appended claims.

What is claimed as new and useful is:

1. In a vehicle station designation sign mechanism of the character described, a pair of spaced, parallel curtain rollers respectively adapted to receive opposite end portions of a curtain to be wound upon one roller simultaneously as it is unwound from the other whereby to present to view a selected portion of the curtain extending between said rollers, and a drive shaft for the rollers having its opposite ends drive-connected to corresponding ends of the rollers, said drive shaft extending lengthwise between said corresponding ends of the rollers and including within its own length a pair of relatively rotatable, concentric members coaxial with and respectively secured to axially spaced portions of the drive shaft, said members being yieldingly connected together.

2. In a vehicle station designation sign mechanism of the character described, a pair of spaced, parallel curtain rollers respectively adapted to receive opposite end portions of a curtain to be wound upon one roller simultaneously as it is unwound from the other whereby to present to view a selected portion of the curtain extending between said rollers, and a drive shaft for the rollers having its opposite ends drive-connected to corresponding ends of the rollers, said drive shaft extending lengthwise between said corresponding ends of the rollers and including within its own length a pair of relatively rotat-

able, concentric members coaxial with and respectively secured to axially spaced portions of the drive shaft, said members being yieldingly interconnected by a coiled spring disposed intermediate said members and having its opposite extremities fixed to said axially spaced portions of the shaft.

3. In a vehicle station designation sign mechanism of the character described, a pair of spaced, parallel curtain rollers respectively adapted to receive opposite end portions of a curtain to be wound upon one roller simultaneously as it is unwound from the other whereby to present to view a selected portion of the curtain extending between said rollers, and drive means for said rollers including a pair of axially spaced, coaxial shaft elements having their outer ends respectively drive-connected to corresponding ends of the rollers, and spring means disposed between and interconnecting said shaft elements to permit differential rotation thereof as the curtain is wound upon one roller and simultaneously unwound from the other.

4. In a vehicle station designation sign mechanism of the character described, a pair of spaced, parallel curtain rollers respectively adapted to receive opposite end portions of a curtain to be wound upon one roller simultaneously as it is unwound from the other whereby to present to view a selected portion of the curtain extending between said rollers, and drive means for said rollers including a pair of axially spaced, coaxial shaft elements having their outer ends respectively drive-connected to corresponding ends of the rollers, a pair of concentric tubes coaxial with and intervening said axially spaced shaft elements, said tubes being respectively connected to said shaft elements and being yieldingly interconnected to permit rotation of said shaft elements and of said rollers at relatively different speeds.

5. In a vehicle station designation sign mechanism of the character described, a pair of curtain receiving rollers disposed in spaced parallel relation to present to view a selected length of curtain extending between said rollers, and means for rotating said rollers simultaneously in the same direction to wind said curtain upon one roller and unwind it from the other, said means including a pair of coaxial shafts respectively drive-connected to corresponding ends of said rollers, said shafts being respectively secured to coaxial tubes arranged in concentric relation, and spring means interconnecting said tubes to provide for limited relative rotation of the shafts and of the rollers operatively associated with said tubes.

6. In a vehicle station designation sign mechanism of the character described, a pair of curtain receiving rollers disposed in spaced parallel relation to present to view a selected length of curtain extending between said rollers, and means for rotating said rollers simultaneously in the same direction to wind said curtain upon one roller and unwind it from the other, said means including a pair of coaxial shafts respectively drive-connected to corresponding ends of said rollers, said shafts being respectively secured to coaxial tubes arranged in concentric relation, and yieldable means interconnecting said tubes to provide a yieldable driving connection between said shafts whereby to compensate for any differential in rotative speeds of the rollers as the curtain is transferred from one roller to the other.

7. In a vehicle sign as defined in claim 6 wherein said yieldable means is in the form of a coil spring embracing the inner tube and having one of its axially spaced terminal extremities fixed to the shaft secured to the inner tube and the other of its said extremities fixed to the outer tube.

8. In a vehicle sign as defined in claim 6 wherein said yieldable means is in the form of an elongated coil spring embracing the inner tube and having its opposite extremities respectively fixed to one end of the outer tube and to the opposite end of the inner tube, and wherein said spring is tensioned to constantly bias one of said rollers in cur-

tain-winding direction whereby to maintain in taut condition the length of curtain extending between the rollers.
